UNITED STATES PATENT OFFICE.

OSCAR H. WISENANT, OF COLORADO SPRINGS, COLORADO, ASSIGNOR OF ONE-THIRD TO J. W. WORSTER, OF ORDWAY, COLORADO, AND ONE-THIRD TO ERNEST F. PARISH, OF COLORADO SPRINGS, COLORADO.

AIR-VALVE.

1,368,871.

Specification of Letters Patent. Patented Feb. 15, 1921.

Application filed May 3, 1920. Serial No. 378,532.

To all whom it may concern:

Be it known that I, OSCAR H. WISENANT, a citizen of the United States, residing at Colorado Springs, in the county of El Paso and State of Colorado, have invented certain new and useful Improvements in Air-Valves; and I do hereby declare the following to be a full, clear, and exact description of the invention, such as will enable others skilled in the art to which it appertains to make and use the same.

This invention relates to instruments for filling containers with air or other gas under pressure and testing the degree of pressure in said container. It is particularly designed for blowing up pneumatic tires and gaging the pressure therein.

Its purpose is to improve combined pressure gages and filling nozzles whereby the pressure in a container may be instantly determined, and, if insufficient, air may be admitted to the container by manipulating one instrumentality.

The invention comprises the novel means illustrated in the drawing, described in the following specification, and defined in the appended claims.

In the accompanying drawings wherein similar reference characters designate corresponding parts throughout the several views:

Figure 1 is a plan view of the improved apparatus;

Fig. 2 is a section taken longitudinally through the body but showing the pressure gage in full line;

Fig. 3 is an end elevation viewed from the inlet side;

Fig. 4 is a view of a perforated disk adapted to open a tire valve when the device is in position for operating.

The nozzle is composed of a body 1, which may be of cast brass or other suitable material, and has an air passage extending through it. At the inlet end 3 an air pipe or hose 4 may be coupled by any suitable form of coupling 5. The outlet port 6 opens at right angles to the inlet 3. The air passage may be formed by coring or otherwise. In line with the inlet the body is bored straight through from end to end. At the inlet end the bore is relatively large and contracts at 6 to form a valve seat which may be ground in order to have a conical surface

that may be air tight. From the valve seat 55 the bore extends nearly to the opposite end where another valve seat 7^a is formed which is also conical and ground air tight. From the seat 7^a a smaller opening 8 opens to the exterior. Intersecting the said bore 60 and extending from the air chamber 9 opposite the outlet port 6 to the exterior of the body is a transverse air passage 10. Into this air passage is threaded an elbow 11 which connects to a pressure gage 12 of any 65 suitable form. I prefer to use a gage of the ordinary steam gage type, as shown. This gage rests upon the flat surface 13 of the body 1. Normally resting on the valve seat 7 is a conical valve head 14, tending to seat 70 by pressure of incoming fluid. A spring 15, shown as a coiled spring, is placed between the valve and an abutment 16 (shown as a washer seated against the coupling 5) near the inlet end of the body, and tends also to 75 press the valve head 14 to its seat 7. The valve head 14 has a reduced stem 17 to permit air to pass freely past the stem into the orifice 18 which connects the inlet with the chamber 9 leading to the outlet. Spaced 80 from the valve head 14 by the stem 17 is a cylindrical piston 19 ground to fit accurately the bore and prevent the passage of air from one end to the other. The cylindrical portion or piston 19 of the valve guides the 85 valve head 14 truly and accurately toward and from the seat 7 in its movements. When the valve head 14 is on its seat the distant end of the piston 19 is at the edge of the passage 10 extending from the air chamber 90 to the pressure gage exposing the openings of said passage into the bore. On the other side of the air passage to the pressure gage is a cylindrical valve head 20 having a conical portion adapted to rest on the conical 95 seat 7^a near the end of the body. The valve head 20 has a stem 21 extending through the orifice 8 to the exterior and on its extremity is formed a push button. The said stem is surrounded by a coil spring 23, one end of 100 which bears upon the body 1 and the other upon the push button 22. The normal tendency of the said valve head 20 is therefore to the open position respecting the air conduit 10 from the air chamber 9 to the 105 pressure gage 12 so that said air conduit is normally open from the pressure gage to the air passage through the body 1. Each of

the valve heads is provided with a screw driver slot whereby they may be readily ground to their seats in case of need.

- Across the outlet port 6 of the valve body 5 is seated a perforated disk 24 having a central projection 25. Outside of this disk is a thick rubber washer or gasket 26. The gasket 26 and disk 24 are held firmly against the body by a screw threaded thimble 27. 10 The function of the projection 25 on the disk is to open a tire valve, such as is conventionally indicated at 28, and the function of the rubber gasket 26 is to make an air tight joint between said tire valve and the 15 outlet port of the body 1, constituting what is sometimes designated a press-on coupling.

When used, for example, in filling a tire with air, the hose 4, it will be understood, is 20 connected to a source of air under pressure or an air pump, not shown. The instrument should then be seized by the hand and the press-on coupling applied to the tip of the tire valve after the cap has been removed, 25 pressing down upon the body 1 to cause the projection 25 on the disk 24 to open the tire valve. Thereupon air from the tire would fill the air passage and act upon the gage indicating the pressure of the air then in the 30 tire. If the pressure is found to be insufficient the thumb or finger pressing upon the push button of the valve will first cut off the flow of air to the pressure gage and then open the inlet valve admitting air from 35 the source of air under pressure into the air chamber and thence into the tire. The thumb being maintained in control of the push button and valve may be released at any time cutting off the inflow of air to the 40 tire and opening the gage to the pressure in the tire, whereby at any time the degree of pressure may be ascertained.

It will be seen that the described combined pressure gage and filler nozzle is 45 compact and convenient, adapted to be manipulated by one hand, constantly under the control of the thumb or finger whereby the exact amount of air to be admitted in order to bring the pressure to a desired amount may 50 be instantly ascertained and by the same motions the inlet of air may be controlled.

Having thus described my invention in the form now best known to me what I

desire to claim and secure by Letters Patent of the United States is as follows:

55

1. In a combined fluid nozzle and pressure gage a body having a straight bore therethrough, a combined puppet valve and piston in said bore, a slide valve in said bore, a pressure gage, a byway from the pressure 60 gage passing through said bore between the piston and slide valve, whereby the slide valve after closing the byway engages and opens the puppet valve.

2. In a combined fluid nozzle and pressure gage, the combination of a body having a straight axis bore therethrough, a valve seat therein, a valve head normally seating thereon under inlet pressure and having a reduced stem in rear of the valve head, a 70 branch passage connecting said bore with an outlet port, a second valve in said bore, a pressure gage, a conduit connecting said pressure gage with said branch passage, said conduit intersecting said bore between said valves, a spring tending to press said second valve under manual control, the range of motion of said second valve in moving to closing position being such that it will open the inlet valve after it has 80 passed the conduit connecting the pressure gage with the air passage.

75

3. In a combined fluid nozzle and pressure gage, the combination of a body having a straight bore therethrough and a 85 branched air passage communicating with said bore and with an outlet at right angles to the inlet, an inlet valve seat in said bore, a valve adapted to seat thereon under inlet pressure, a piston stem on said valve 90 guided by said bore and fitting air tight therein, a reduced portion between said piston stem and the valve head, a piston valve fitting said bore, a pressure gage, a conduit connecting the pressure gage with said 95 branched passage and intersecting the bore between said piston stem and said piston valve, a spring on said piston valve tending to move it in a position to expose said conduit, a push button connected to said piston 100 valve, said piston valve being adapted to open the inlet valve when moved to close said conduit.

In testimony whereof I affix my signature.

OSCAR H. WISENANT.
